DESIGN FOR A WRITING SECRETARY

Dmytro Stec, Dearborn, Mich.

Application February 12, 1948, Serial No. 144,426

Term of patent 7 years

(CL. D74—1)

To all whom it may concern:

Be it known that I, Dmytro Stec, a citizen of the United States, residing at Dearborn, in the county of Wayne and State of Michigan, have invented a new, original, and ornamental Design for Writing Secretary, of which the following is a specification, reference being had to the accompanying drawing, forming part thereof.

4—4 of Figure 1.

I claim:

The ornamental design for a writing secretary, as shown.

DMYTRO STEC.
